INVENTOR.

BY *Ralph L. Brown*

ATTORNEY.

UNITED STATES PATENT OFFICE.

EMERY M. McVICKER, OF MILWAUKEE, WISCONSIN.

RAIL ANTICREEPER.

Application filed April 3, 1926. Serial No. 99,476.

This invention relates to rail anti-creepers. One object of the present invention is the provision of improved means for securely fastening the clamp to the rail without flexing or distorting the clamp when placing it in position. Rail anti-creepers which depend upon their resiliency to hold them in position yield when creeping occurs so that they loosen, and thus become ineffective.

Another object is the provision of simple securing means which renders the clamp applicable to rails having base flanges of varying thicknesses.

Other objects and advantages will appear from the following description of illustrative embodiments of the present invention.

In the drawings:

Fig. 1 is a perspective view of the clamp shown attached to the usual tie supporting the rail.

Fig. 2 is a perspective of the rail clamp shown in Figure 1.

Fig. 3 is a perspective of a slightly modified form of rail clamp which unlike the form shown in Figure 2 is bent from bar stock.

Fig. 4 is a view similar to Figure 1 illustrating another form of rail anti-creeper in combination with a rail tie-plate.

Fig. 5 is a perspective view of the modified clamp shown in Fig. 4.

Fig. 6 is a view of an anti-creeper similar to one shown in Figure 5, but modified to have the flared tail in the plane of the jaw rather than offset from it.

The clamps selected for illustration are shown attached to the usual rail 10 which is supported by the usual tie 12.

The clamp 13 comprises a base portion 14 terminating in a short upstanding lug 15 at one end thereof, which is adapted to engage the rail base and base flange 19 of the standard rail 10. The other end of the base portion 14 of the clamp 13 has an upstanding integral tang 16 bent over at 17, to provide a rigid hook or jaw 18 partially overlying the base portion 14, and adapted to overhang the base flange 20 of the rail 10. The face of the jaw 18 which confronts the rail engaging surface of the base portion 14

is notched as at 21 or otherwise shaped to provide an appropriate retaining seat for the securing means 27.

The securing means in this instance consists of a wedge 22 which is guided by and partially housed within the notch 21 of the jaw 18, and engages the top of the rail flange 20 so as to effect a firm grip between the clamp 13 and the rail 10. It is to be noted that there is enough clearance between the jaw 18 and the top of the base flange underlying it, to permit the removal of the clamp by pivoting it about the tang 16 until the lug 15 clears the base of the rail 10. The clip is then free to be removed. To securely fasten the clamp to the rail its U-shaped portion defined by the base 14, the tang 16, and the hooked end 18 is placed over the side flange 20, and the clip is then pivoted about this U-shaped end until the base portion 14 lies adjacent to the rail base. In this position, the lug 15 engages the edge of the base flange 19. The wedge 22 is then driven into and between the jaw 18 and the upper face of the side flange 20 in order to securely bind the clamp to the rail base.

The wedge is driven up from time to time in order to compensate for wear, and is preferably retained in position by bending up its end in the manner indicated at 23. Any tendency to creep in the longitudinal direction as indicated by arrow A is prevented by the engagement of the base 14 of the clamp against the corresponding vertical side surface 24 of the tie 12. The engagement of the clamp with the tie at the time of creeping causes the clamp to rock slightly thereby increasing its grip upon the rail.

The tie engaging portion 13 of the clamp is preferably lowered as at 13' so as to insure its engagement with the wall of the tie without crushing or otherwise marring the upper portion of the tie wall, during the occurrence of any longitudinal creeping of the rail. The clamp shown in Figure 2 is forged so as to present the thickened base portion 13. To eliminate the costly forging operations, however, the clamp in actual practice is shaped from bar stock as shown

in Figure 3. In this form of clamp, the rail base contacts with the shoulders 14 defined by the end walls 15—16 and the depressed portion 13'.

Another form of clamp illustrated in Figures 4 and 5 embodies features of the present invention. It comprises a substantially U-shaped portion 25 having an upper jaw 26 overlying the base flange 30, and a lower jaw 27 seated in a cut-out portion of the tie plate, and underlying the base flange 30. This U-shaped portion is adapted to loosely embrace the edge of the flange 30. It is securely bound to the flange of the rail by means of the wedge fully described in connection with the clip shown in Figures 1 and 2. The cut-out portion in the tie plate 11, consists of a rectangular opening terminating on one edge thereof. The U-shaped portion 25 is in engagement with the shoulder 31 of the opening, and is retained thereby in rail gripping position. The other shoulders of the cut-out portion abut against the adjacent walls of the clamp as is apparent from the drawing. The tie plate 11 is secured to the supporting tie 12 by means of the spikes 32 in the usual manner.

In order to have the clamp engage the vertical wall of the tie, the U-shaped portion is provided with downwardly extending integral extension 28 which is off-set from the plane of the jaw portion 25 so as to present a shoulder 29 adapted to rest on the upper horizontal surface of the tie 12.

Still another form of anti-creeper is shown in Figure 6, wherein the tail 28 is in the plane of the jaws 26—27, and is flared outwardly as at 33. In this instance the tie plate 11 overhangs the tie 12. A rectangular opening in the overhanging portion of the tie plate receives the clamp so that the tail 28 lies adjacent to the vertical wall of the supporting tie 12, whereas the flared portion 33 will abut against the lower edge 34 of the opening. This construction limits the upward movement of the clamp, and thus effectively prevents the rail from excessive lifting and from rocking out of place.

Various changes may be made in either of the embodiments of the invention hereinabove described, without departing from or sacrificing any of the advantages of the invention as defined in the appended claims.

I claim:

- 55 1. In an anti-creeper for railway rails the combination with a member having a portion engageable with a vertical face of a tie, a portion engageable with and beneath a rail flange, and a portion overlying the rail flange, of a longitudinally tapered wedge interposed between said overlying portion and the top of the rail flange for effecting a positive gripping pressure vertically applied between said member and flange.
- 60 2. In an anti-creeper for railway rails the

combination of a member having a portion for embracing an edge of a rail flange, said embracing portion including an element for overlying the flange, a longitudinally tapered wedge interposed between said element and the top face of the flange to bind said member to the rail, and a seat in said overlying element for receiving and positioning said wedge, said member having a portion for engagement with the vertical face of a tie to thereby hold said rail against creeping.

3. In an anti-creeper for railway rails the combination of a member having a portion for embracing an edge of a rail flange, said embracing portion including an element for overlying the flange, means for retaining said portion in edge embracing position, and a longitudinally tapered wedge interposed between said element and the top face of the flange to effect a positive gripping pressure vertically applied between said member and flange, said member having a portion engageable with the vertical face of a tie to thereby hold said rail against creeping.

4. In an anti-creeper for railway rails the combination of a member having a portion for embracing an edge of a rail flange, said embracing portion including an element for overlying the flange, a wedge interposed between said element and flange for binding said member to the rail, a seat in said element for receiving and retaining said wedge, and means depending from said member for engagement with a vertical face of a tie to hold the rail against creeping.

5. In an anti-creeper for railway rails the combination of a member having a portion for embracing an edge of a rail flange, said portion including an element for overlying the flange, a plate having a recess for receiving said member to retain the same in edge embracing position, and a wedge interposed between said element and the flange for binding said member to the rail, said member having a portion engageable with a front face of a tie to hold the rail from creeping.

6. In an anti-creeper, the combination with a tie plate provided with an opening therein, of a clamp having jaws positioned in said opening and adapted to embrace the base flange of a rail, means interposed between said jaws and rail to secure said clamp to the rail, and tie engaging means depending from said clamp for holding the rail against creeping.

7. In an anti-creeper, the combination with a tie plate provided with an opening therein, of a clamp having jaws positioned in said opening and adapted to embrace the base flange of a rail, means interposed between said jaws and rail to secure said clamp to the rail, and tie engaging means depending from said clamp and laterally offset from said jaws for preventing creeping of the rail.

8. In an anti-creeper, the combination with a tie plate provided with an opening therein, of a clamp having jaws positioned in said opening and adapted to embrace the base flange of a rail, means interposed between said jaws and rail to secure said clamp to the rail, and tie engaging means depend-

ing from said clamp, and projecting underneath the tie plate to prevent upward movement of said clamp. ¹⁰

In witness whereof, I hereunto subscribe my name this 30th day of September, 1925.

E. M. McVICKER.
